FIG. 12.

UNITED STATES PATENT OFFICE.

CLARENCE G. FISHER, OF ROCHESTER, NEW YORK.

PAPER-FASTENER.

1,280,434.

Specification of Letters Patent.

Patented Oct. 1, 1918.

Application filed January 27, 1916. Serial No. 74,642.

To all whom it may concern:

Be it known that I, CLARENCE G. FISHER, a citizen of the United States, and resident of Rochester, Monroe county, State of New York, have invented certain new and useful Improvements in Paper-Fasteners, of which the following is a specification.

This invention relates to paper fasteners and more particularly to that type of fasteners by means of which a plurality of papers or letters are pinned and securely held together. More specifically, the invention relates to certain improvements in the constructions disclosed in my prior application, No. 735,782, filed December 9, 1912.

The objects of the invention are to provide an improved fastener of this type which is extremely simple in construction, inexpensive to manufacture and which will so hold the papers, when in use, that in lifting them the ends of the front and back members cannot pass through the perforations in the papers.

A further object is to provide a front member having the above advantage and also being adapted to support the points so that the latter may be bent in either direction.

A further object of the invention is to provide a fastener which may be readily attached to the top of a file of papers in order to form an extension thereof.

Other objects and the features of novelty will be apparent from the following description taken in connection with the accompanying drawings, in which,

Figure 1 is a plan view of the upper portion of a file of papers secured together by a fastener embodying the invention;

Fig. 2 is a section on the line 2—2 of Fig. 1;

Fig. 3 is a perspective view of the main part of the backing member illustrated in Figs. 1 and 2;

Fig. 4 is a transverse section on the line 4—4 of Fig. 3;

Fig. 5 is a view similar to Fig. 3, but showing a modification;

Fig. 6 is a section on the line 6—6 of Fig. 5;

Fig. 7 is a view similar to Fig. 3 and showing still another form;

Figs. 8 to 12 illustrate different forms of the wire structure used with the parts shown in Figs. 3, 5 and 7;

Fig. 13 is a view similar to Fig. 2, but

showing the manner in which the fasteners are secured together in extending a file.

Referring to the drawings and more particularly to Figs. 1 and 2, 20 indicates a

stack of papers secured together by a fastener which comprises a backing member or base, the main portion 21 of which is arranged on the bottom of the pile between the perforations 22 and 23 in the papers.

The portion 21 of the backing member has its edges struck up as shown in Figs. 3 and 4 and at its ends is provided with the flexible points 24 and 25, these points extending substantially at right angles to the portion 21.

The backing member may also include a wire structure, consisting of a body portion 26 arranged between the struck-up edges of the portion 21, which at its ends has a plurality of loops 27, 28 through which the

points 24 and 25 project, as most clearly shown in Fig. 1. In order to secure the wire structure to the portion 21 of the backing member, the edges of the latter are pressed together at one or more points, as

indicated at 28' in Fig. 3. In some instances it may be necessary to cut or turn the edges at the points 28' in order to prevent buckling in the operation of pressing the edges together.

In assembling the parts of the backing member, the points 24 and 25 are projected through the loops at the ends of the wire structure and the body portion 26 of the wire structure is forced between the edges of the main portion 21 at the points 28', the

material having sufficient elasticity to secure the portion 26 of the wire structure at the points 28'.

The backing or base member as thus constructed consists of a comparatively stiff part extending along the bottom of the stack of paper, which is secured together by the fastener, and the flexible points projecting from the comparatively stiff portion. It

will be understood that the ends of the wire structure may be formed in other shapes than that illustrated in Fig. 1, but the structure illustrated in Fig. 1 has especial advantages when used as a front member, as hereinafter described, and, it being desirable to have the front member and the wire structure of the backing member alike, it is

considered preferable to use a structure embodying a plurality of loops as each end. One advantage of the structure illustrated in Fig. 3 is that it may be formed in dies

by a single operation and thus produced in

large quantities at a very low cost and, furthermore, the fasteners may be sold with the two wire members, which go with each, detached therefrom, so that there will be 5 no expense, in connection with the manufacture of the fasteners, in assembling the parts.

The front member illustrated in Fig. 1 is especially adapted for this use on account of 10 having the plurality of loops at each end, one loop being arranged within the other. As illustrated the points 24 and 25 are passed through the inner loops 27 which closely fit the edges of the points and facilitate bending 15 the points in either direction by constituting supports for the opposite sides of the points over which the points may be bent. It is desirable that the edges of the loops through which the points extend shall closely 20 fit the points in order to avoid undue shifting of the front member and since the openings 22 and 23, which are made by the perforators commonly in use, are relatively 25 large, the outer loops 28 are provided to prevent the ends of the fastener working through the openings when the papers are lifted or turned back over the top of a stack. The outer loop at each end is preferably of rectangular form so that the papers 30 may be bent over substantially straight portions 29, thus avoiding, to a large extent, mutilation of the papers by the fastener.

In Figs. 5 and 6 another form of the invention is illustrated and in this form the 35 body portion of the backing member is channel shaped, as indicated at 30, and has laterally projecting flanges 31 on its opposite sides with inwardly turned ears 32 adapted to retain the wire structure 33 in position. 40 The form shown in Fig. 7 is the same as that shown in Fig. 3, with the exception that the edges are not pressed together as at the points 28' in Fig. 3.

In Figs. 8 to 12, inclusive, various forms 45 of the wire structures are illustrated and it will be noted that each of these structures has its end portions provided with a plurality of loops, one within the other, so that the various forms are equivalent to the form 50 illustrated in Fig. 1.

In Fig. 13 there is illustrated the method of building up or extending a file when the 55 capacity of the original fastener has been reached. In extending the file the front member is removed and the points 34 and 35 are projected through the end loops of the backing member of the extension fastener, the points then being turned outwardly 60 against the top sheet of the original file. 65 This secures the backing member 36 of the extension fastener and papers may then be arranged on the points 37 and 38 of the latter in the usual way, a front member 39 being, of course, employed to retain the papers in position.

It will be evident to those skilled in the art that the parts may be arranged in various combinations and accomplish the results sought and while I have illustrated several modifications and arrangements, I do not 70 limit myself to these forms of the invention but claim all equivalent constructions and arrangements which are within the scope of the appended claims.

Having thus described the invention, what 75 is claimed and desired to be secured by Letters Patent is:

1. A paper fastener comprising a backing member provided with flexible points adapted to be arranged at substantially right 80 angles to the body thereof, and a front member made of wire and having at each of its ends a plurality of loops one within the other through which said points are adapted to pass, the front member being secured by 85 bending the points into a plane substantially parallel with the front member.

2. A paper fastener comprising a backing member provided with flexible points adapted to be arranged at substantially right 90 angles to the body thereof, and a front member made of wire and having at its ends a plurality of loops in the same plane adapted to receive said points and support the same when they are bent in either direction.

3. A paper fastener comprising a backing member provided with flexible points adapted to be arranged at substantially right angles to the body thereof, and a front member made of wire and having at its ends a 100 plurality of loops in the same plane adapted to receive said points, the outer of said loops having substantially straight sides extending longitudinally of the front member and over which the paper may be turned.

4. A paper fastener comprising a front member and a backing member, the backing member having a body portion formed with struck-up longitudinal edges and integral 105 flexible points at the ends of the body portion adapted to be arranged at right angles to the latter, said member including a wire having a body portion arranged between said struck-up portions and having loops surrounding said points, and the front member having end portions through which said points may be passed.

5. A paper fastener comprising a front member and a backing member, the backing member having a body portion, the edges of 110 which are struck up and portions of the edges bent inwardly, and integral flexible points at the ends of the body portion arranged substantially at right angles to the latter, said backing member including a wire 115 having a body portion arranged between said struck-up portions and secured in position by the said portions which are bent inwardly, said wire having end loops embracing said points, and the front member hav- 120 125 130

ing end portions through which said points may be passed.

6. A paper fastener comprising a front member and a backing member, the backing member having a body portion formed with struck-up longitudinal edges and flexible points at the ends of the body portion adapted to be arranged at right angles to the latter, said backing member including a wire 10 having a body portion arranged between said struck-up portions, the wire having means at the ends to embrace said points, and the front member having end portions through which said points may be passed.

15 7. A paper fastener comprising a front member and a backing member, the backing

member having a body portion, the edges of which are struck up and portions of the edges bent inwardly, and flexible points at the ends of the body portion arranged substantially at right angles to the latter, said member including a wire having a body portion arranged between said struck-up portions and secured in position by the said portions which are bent inwardly, said wire 20 having means at the ends to engage said points, and the front member having end portions through which said points may be passed.
